UNITED STATES PATENT OFFICE.

FRANCIS H. TOBIAS, OF NEW YORK, N. Y.

LAMP.

1,034,536.

Specification of Letters Patent.

Patented Aug. 6, 1912.

Application filed October 23, 1911. Serial No. 656,086.

To all whom it may concern:

Be it known that I, FRANCIS H. TOBIAS, a citizen of the United States, residing at New York, in the county of New York and State of New York, have invented certain new and useful Improvements in Lamps; and I do hereby declare the following to be a full, clear, and exact description of the invention, such as will enable others skilled in the art to which it appertains to make and use the same.

My invention relates to lamps and more particularly to head-lights for automobiles or the like, and has for an object to provide a means whereby a lamp may have a powerful beam of light for use where desired and a subdued light for use in cities.

Another object of my invention is to have a lamp with the usual burner and reflector and to have a dimmer interposed therebetween, said dimmer being made in sections and said sections being swung from one plane to another to give the desired effects according to the conditions.

Further objects of my invention is the means for operating the sections of the dimmer simultaneously.

Further objects of my invention will be apparent from the following specification, appended claims and drawings in which:—

Figure 1 is a horizontal sectional view through a lamp showing the elements of my invention applied thereto. Fig. 2 is a vertical sectional view through the lamp showing the elements of my invention in elevation. Fig. 3 is a similar view to Fig. 1 with the parts moved in their opposite position and the solenoid shown in section. Fig. 4 is a rear elevation of my device. Fig. 5 is a bottom view of the lower ends of the shafts supporting sections of the dimmer.

Referring more specifically to the drawings there is shown a housing 10 of the common type in which there is a reflector 11 common to this type of a lamp and a pillar 12 for a burner for acetylene gas but this pillar may be replaced by a support for an arc light if so desired. A plate 13 having one end thereof bent as at 14 and bearings formed in the end of said portion, the plate being further bent as at 15 to form substantially a semi-circular portion, which portion is intended to partly surround the pillar 12 and the portion 16 extending in advance of the portion 15 is somewhat broadened and curved to conform to the shell on the sole-

noid 17 to be hereinafter described. A plate 18 which has one end thereof bent as at 19, the ends of which are formed into bearings to receive a vertical shaft to be hereinafter described and a portion of which bent portion is cut away to expose a portion of the shaft carried in the bearings to be hereinafter described and the opposite end of said plate is bifurcated and bent as shown at 20 to partly surround the pillar and said ends being resilient so that when the plate 18 is secured to the plate 13 the curved portion 15 of the plate 13 and the ends 20 securely clamp the pillar 12. Vertical shafts 21 and 22 are secured in the bearings in the end portions 14 and 19 respectively and on the shafts 21 and 22 are the gears 23 and 24 respectively, which gears intermesh so that movement is transmitted from the shaft 22 to the shaft 21 through said gears. The shaft 22 is provided with a crank 25 to which the link 26 is pivotally connected and the link is again pivotally connected to the core 27 of the solenoid 17. This solenoid is divided into independent windings 28 and 29 so as to cause the core to move from either end toward the other according to the winding energized and from the adjacent ends of the windings 28 and 29 is a wire 30 which passes through a battery or the like to a switch. The opposite end of the winding 28 is connected to the switch by the wire 31 and the winding 29 being connected to the opposite end of the switch by the wire 32. The circuit through the windings 28 and 29 is closed by the points 33 and 34 which when closed contact with the terminals of the wires 31 and 32 respectively. The wires 31 and 32 which lead from the solenoid to the switch may be placed in any convenient position such as within reach from the driver's seat and it is obvious that by closing the circuit of either of the windings 28 or 29 the core 27 will move in the direction of the energized winding.

The lower ends of the shafts 21 and 22 are provided with cranks 35 which carry pins at their outer ends and which pins are connected to one another by a spring 36, said cranks being so positioned on the lower ends of the shafts as to cause the shafts to remain in fixed position under tension of the spring 36 when rocked to either side of the axis of the shafts and secured to the upper ends of the shafts 21 and 22 are the blades 37 and 38 respectively which constitute the

dimmer of said light. The blade 37 is slightly less than a semi-circle while the blade 38 is somewhat larger than a semi-circle so that when as shown in Fig. 1 of the drawings the straight edges of the blades overlap to prevent any rays of light striking the reflector which, of course, causes only the rays of light emanating from the forward side of the flame to produce the lighting when a subdued light is desired. When it is desired to derive the full benefit from the rays of light emanating from the flame in all directions, the solenoid 27 is caused to advance within the winding 28 which in turn rocks the shafts 21 and 22 a quarter of a turn which in turn causes the blades 37 and 38 to swing correspondingly and turn their thin edges to the light thereby permitting the rays of light from the backside of the flame to strike the reflector and thereupon be projected forwardly therefrom. The upper ends of the blades 37 and 38 at points in axial alinement with the axis of the shafts 21 and 22 are held in spaced relation by a member 39.

I am aware that dimmers have been placed in lamps between the light and the front side of the lamp and also an enlarged and single piece of metal interposed between the light and the reflector which piece is swung on a pivot carried by the housing but my invention is to provide a simple and convenient method of forming a dimmer between the

light and the reflector when desired and to cause the dimmer to occupy a minimum of space within the rays of the light when a powerful light is desired.

Having thus described my invention, I claim:—

1. In combination with a lamp having a burner and a reflector, a dimmer comprising two substantially semi-circular overlapping plates, spaced vertical shafts for said plates, a clamping member secured to said burner, and having bearings for said shafts, and means carried by said clamping member to rock said shafts.
2. In a dimmer for automobile or other lamps, two substantially semi-circular plates, a bracket member secured to the burner of said lamp, bearings formed in said bracket member, vertical shafts mounted in said bearings, said shafts having geared connection to one another, each of said shafts having a crank on the lower end thereof, the free ends of said cranks having spring connection with one another and said cranks being positioned to retain said shafts in fixed position in either limit of their rocking play and means to rock said shafts.

In testimony whereof I affix my signature in the presence of two witnesses.

FRANCIS H. TOBIAS.
